UNITED STATES PATENT OFFICE.

ISIDOR ROSENBLATT, OF BROOKLYN, NEW YORK.

DESIGN FOR A LIGHTING FIXTURE.

Application filed May 24, 1929. Serial No. 31,385. Term of patent 14 years.

To all whom it may concern:

Be it known that I, ISIDOR ROSENBLATT, a citizen of the United States, residing at Brooklyn, in the county of Kings and State of New York, have invented a new, original, and ornamental design for a Lighting Fixture, of which the following is a specification, reference being had to the accompanying drawing, forming part thereof, in which

The figure is a view slightly in perspective showing my new design.

I claim:

The ornamental design for a lighting fixture, as shown.

ISIDOR ROSENBLATT.
